BULLETIN BOARD

George E. Fox, Chicago, Ill.

Application March 13, 1939, Serial No. 261,433

3 Claims. (Cl. 40—125)

The present invention relates generally to boards for use in posting bulletins. More particularly the invention relates to that type of board which is provided with means whereby it may be supported or hung against a wall and is adapted to have bulletins secured removably against its front face by way of thumb tacks.

It has heretofore been customary or the accepted practice in the fabrication of a bulletin board of this type to employ a panel of cork for receiving the points of the thumb tacks. Such a panel although it has manifest advantages over a panel of felt or soft wood or a combination of panels of such materials, is subject to the objection that repeated penetration or lodgment of the points of the thumb tacks in it cause holes which in addition to being unsightly make it difficult or impossible to place the thumb tacks in the same place and hence materially restrict the life of the board as a whole.

One object of the invention is to provide a bulletin board which is an improvement upon and has greater durability than previously designed boards with cork front panels by reason of the fact that its front panel, that is, the panel for receiving the points of the thumb tacks, is formed of a comparatively soft spongy material such as sponge rubber which, in addition to permitting the points of the tacks to be readily embedded or lodged in it, grips the points securely and permits them to be removed without leaving holes in the front panel.

Another object of the invention is to provide a bulletin board of the last mentioned character in which the front panel of sponge rubber is less in thickness than the length of the points of thumb tacks of standard size and is backed and supported against buckling by a cardboard back panel which is adapted to receive and grip frictionally and securely the sharp needle like extremities of the thumb tack points and thus contacts with the sponge rubber front panel to hold the thumb tacks in place without likelihood of accidental displacement.

A further object of the invention is to provide a bulletin board which is generally of new and improved design and in addition to having a pleasing appearance may be manufactured at an extremely low cost.

Other objects of the invention and the various advantages and characteristics of the present bulletin board will be apparent from a consideration of the following detailed description.

The invention consists in the several novel

features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a perspective view showing a bulletin board embodying the invention in its operative position and with bulletins affixed thereto by way of thumb tacks of conventional or standard size;

Figure 2 is a horizontal section;

Figure 3 is an enlarged fragmentary section taken on the line 3—3 of Figure 1 and illustrating in detail the design and arrangement of one of the eyelets which constitute the means whereby the board may be supported against a wall; and

Figure 4 is an enlarged section taken on the line 4—4 of Figure 1 and showing the manner in which the front panel of sponge rubber and the rear panel of cardboard coact to hold in place a bulletin supporting thumb tack.

The bulletin board which is shown in the drawing constitutes the preferred embodiment of the invention. It is adapted to be hung or supported against a wall and to have bulletins or notices secured to it by way of thumb tacks T of standard size and comprises a front panel 5, a back panel 6, a frame 7, and a pair of eyelets 8. The tacks consist of enlarged heads t, and points t', as shown in Figure 4, and are adapted when used to attach the bulletins to the board to be forced inwards by the thumb in such manner as to bring the points thereof into embedded relation with the front and rear panels. The tips or outer extremities of the points of the tacks are sharply pointed or needle-like so that the points are capable of being forced readily into the panels.

The front panel 5 is rectangular and fits against the back panel 6. It is formed of sponge rubber and preferably has non-porous outer and inner faces. The thickness of the front panel is less than the length of the points t' of the tacks. In practice it has been found that effective anchoring of the points of the tacks is obtained when the thickness of the front panel is slightly greater than half of the length of the tack points. The back panel 6 is the same in shape and size as the front panel 5. It is formed of cardboard and is secured to the front panel by way of a layer 9 of any suitable adhesive material. As shown in Figure 2, the adhesive is coextensive

with the adjoining inner faces of the two panels. The back panel is the same in thickness as the front panel and serves to stiffen, and thus prevent sagging of, the front panel 5. In addition, 5 it is adapted to receive the needle-like tips or outer extremities of the points t' of the tacks T and coats with the sponge rubber panel 5 to hold the tacks securely in place. Because of the substantial permanent elasticity of sponge rubber 10 the points of the tacks when withdrawn from the board leave in the front panel no holes which are unsightly and would tend to limit or restrict the durability of the board as a whole. By reason of the fact that the front panel is less in 15 thickness than the points of the tacks are long and is backed by the cardboard back panel 6 the points of the tacks when inserted into the board pass readily through the front panel and into the back panel. When the thumb tacks T 20 are in place in the board the front panel because of its elastic nature grips frictionally and securely the inner portions of the points of the tack and the back panel 6 grips and forms a firm anchorage for the needle-like tips or outer extremities of the points. As shown in Figure 4, 25 the combined thickness of the front and back panels is greater than the length of the points of the tacks with the result that when the tacks are in place the needle-like tips do not project 30 beyond the rear face of the back panel.

The frame 7 is of the channel variety and extends around the top, side and bottom portions of the two panels 5 and 6, as shown in Figure 1. It is preferably formed of metal and embodies 35 inturned laterally spaced side flanges 10 which fit against and secure in abutting relation the marginal portions of the front and back panels 5 and 6.

The eyelets 8 are located at and extend through 40 the upper corners of the board. They extend through aligned holes in the front and back panels 5 and 6 and are adapted in connection with hooks or other attaching devices to hold the board in place. The ends of the eyelets have 45 outwardly extending flanges 11 which lap the outer faces of the front and back panels and serve to hold the eyelets against axial displacement with respect to the panels.

When the board is in its operative position 50 and it is desired to post bulletins on the board, it is only necessary to place the bulletins against the front face of the front panel 5 of sponge rubber and then force the points of the thumb tacks through the two panels, as hereinbefore described. When the thumb tacks are in place 55 the heads t prevent dislodgment of the bulletins from the points of the tacks and the points are gripped and held not only by the sponge rubber front panel but also by the cardboard back panel 6. When the thumb tacks T are withdrawn from 60 the board in connection with removal of the bulletins no unsightly holes are left in the front panel 5, as heretofore pointed out.

The herein described bulletin board possesses 65 extremely long life and effectively and efficiently fulfills its intended purpose. By reason of the

fact that the sponge rubber front panel is less in thickness than the pins of the tacks are long but a small amount of sponge rubber is needed in connection with fabrication of the board and the board as a whole may thus be produced at a 5 low and reasonable cost.

The invention is not to be understood as restricted to the details set forth, since these may be modified within the scope of the appended claims, without departing from the spirit and 10 scope of the invention.

Having thus described the invention, what I claim as new and desire to secure by Letters Patent is:

1. As a new article of manufacture, a board 15 adapted to have bulletins posted thereagainst by way of thumb tacks of predetermined or standard size and comprising a bulletin receiving front panel adapted to receive and have embedded therein the head adjoining portions of the tack points and formed of a sheet of sponge rubber with substantially nonporous front and back faces, in order that said portions of the tack points are gripped frictionally and elastically when embedded therein and the points leave no 20 holes when withdrawn therefrom, and a comparatively stiff coextensive back panel fitting against, and having the entire front face thereof adhesively secured to, the back face of the front panel and adapted to receive and grip frictionally 25 but releasably the tips of the tack points.

2. As a new article of manufacture, a board 30 adapted to have bulletins posted thereagainst by way of thumb tacks of predetermined or standard length and comprising a bulletin receiving front panel adapted to receive and have embedded therein the head adjoining portions of the tack points and formed of a sheet of sponge rubber with substantially nonporous front and back faces in order that the tack points are gripped 35 frictionally and elastically when embedded therein and the points leave no holes when withdrawn therefrom, and a coextensive cardboard back panel fitting against, and adhesively secured throughout the entire area of the front face 40 thereof to, the back face of the front panel and adapted to receive and grip frictionally but releasably the tips of said tack points.

3. As a new article of manufacture, a board 45 adapted to have bulletins posted thereagainst by way of thumb tacks of predetermined or standard size and comprising a bulletin receiving front panel adapted to receive and have embedded therein the head adjoining or inner portions of the tack points and formed of a sheet of sponge 50 rubber with a substantially nonporous front face, in order that such portions of the tacks are gripped frictionally and elastically when embedded therein and the points leave no holes when withdrawn therefrom, and a coextensive comparatively stiff cardboard back panel of substantially 55 the same thickness as the front panel fitting against and secured to the back face of the front panel and adapted to receive and grip frictionally but releasably the tips of the tack points.

GEORGE E. FOX. 60
